UNITED STATES PATENT OFFICE.

SIMON B. PARKER, JOSEPH K. NEWELL, AND JAMES A. TURNBULL, OF SPRINGFIELD, MASSACHUSETTS.

DESIGN FOR A GRAVE-MARKER.

SPECIFICATION forming part of Design No. 23,744, dated October 23, 1894.

Application filed January 24, 1894. Serial No. 497,936. Term of patent 3½ years.

To all whom it may concern:

Be it known that we, SIMON B. PARKER, JOSEPH K. NEWELL, and JAMES A. TURNBULL, citizens of the United States, residing at Springfield, in the county of Hampden and State of Massachusetts, have invented and produced a new and original Design for a Marker for Graves, of which the following is a specification, reference being had to the accompanying drawing, forming a part thereof.

The present invention has for its object to provide an appropriate design for a grave-marker to be used upon the graves of Union soldiers and sailors, and consists in a design substantially as shown in the accompanying drawing which represents a front elevation of a grave-marker embodying the design, which consists in the following leading features: a representation of a shield with the stars and stripes thereon which forms the central figure, and upon this shield is a rep-

resentation of an eagle with out-stretched wings, and a laurel wreath encircling the shield.

The grave marker has a stem B for inserting in the ground, and between the laurel wreath A and the shield, is a surface C which forms the back ground to the marker.

Having now fully described our design, what we claim as new, and desire to secure by Letters Patent, is—

The design for a grave marker, substantially as shown and described.

In testimony that we claim the above we have hereunto subscribed our names in the presence of two witnesses.

SIMON B. PARKER.
JOSEPH K. NEWELL.
JAMES A. TURNBULL.
